(57) **CLAIM**

The ornamental design for a servo amplifier as shown and described.

DESCRIPTION

FIG. 1 is a front perspective view of the front, right, and top sides of a servo amplifier showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The evenly-dashed broken lines shown in the drawings represent portions of the servo amplifier that form no part of the claimed design.

The dash-dot broken lines shown in the drawings represent the boundaries of the claimed design and form no part of the claimed design.
